H. PRADAS

FIRE ALARM AND DETECTOR

Filed April 8, 1926

INVENTOR,
Henry Pradas;
BY G.E. Maynard,
ATTORNEY.

UNITED STATES PATENT OFFICE.

HENRY PRADAS, OF LOS ANGELES, CALIFORNIA, ASSIGNOR OF ONE-THIRD TO MARTIN KROEGER AND ONE-THIRD TO LOUIS CARRILLO, BOTH OF LOS ANGELES, CALIFORNIA.

FIRE ALARM AND DETECTOR.

Application filed April 8, 1926. Serial No. 100,569.

This invention relates to signal apparatus and more especially to temperature controlled means for completing an electric circuit associated with any desired audible, visible or other apparatus for effecting the alarm.

An object of the invention is to provide means operative by the expansion of air which is heated in the event of the increase of heat above a predetermined degree.

Another object is to provide an apparatus of simple, inexpensive form, and which, when once set for operation at a predetermined degree of temperature, will thereafter be in constant readiness for action, and whose parts are not liable to be readily disadjusted or placed out of order except by intent, unless by complete destruction.

Additional objects are to provide a thermosensitive, automatically acting device which can be easily regulated to function reliably at a rise in temperature above the desired high degree in any given place of use or installation; to provide a device which can be tested from time to time without making any adjustments of parts, and without resulting in injury or destruction to the instrument or any of its elements; to provide a device which has no acids and no low point fusing media as controlling agents which are destroyed at each completion of its designed operation; and therefore a broad object is to provide a device which will operate to give a continuous signal until the temperature falls to the predetermined point, or until the signal is switched off, or the apparatus is made inoperative by fire after the signal has been effected by the device.

Other objects and advantages will be made manifest in the following specification of apparatus embodying one form of the invention; it being understood that modifications, variations and adaptations may be resorted to within the spirit and scope of the invention as here claimed.

Figure 1 is a vertical section of the device.

Figure 2 is a cross-section through the air cells or tubes.

Figure 3 is a view showing one adaptation of the invention in a signal system.

The circuit closing control is here shown as including a series of air tubes 2 whose tops are closed by a crown or top plate 3 from which the tubes extend down in parallel

relation to a manifold or base 4 having holes 5 for the ends of the tubes 2. These open at the bottom immediately over a thin diaphragm 6 which is secured at its margin to the margin of the manifold 4 beyond the outlets of the air tubes so that the area of the diaphragm is subjected to pressure of air expanding from any one or more of the tubes.

Since the diaphragm lies close to the face of the manifold 4 it will be seen that but a very slight change in temperature will be sufficient to cause expansion of air in the tubes and the expanding air acts instantly on the diaphragm so that this will be bulged outward. This action is utilized to close an electric circuit.

Below the bottom of the diaphragm is an adjustable screw 10, preferably having a platinum contact terminal 11 to engage an opposed part of the diaphragm, which is preferably of thin copper. The screw 10 is mounted in a cross-bar 12 suitably attached to the manifold 4.

A margin ring 13 is here shown as secured to rods 14 passing up through the diaphragm and manifold and to the crown 3.

The bar 12 is insulated from the other parts and from it leads a conductor 17. From the manifold leads a conductor 18. These conductors lead to any desired signal apparatus as bells B, which may be at any desired station or location at which the signal is to be given.

Therefore, when the screw has been set at a desired distance from the diaphragm 6 normal temperature changes may occur without consequence but when the temperature reaches a given point, determined by the screw spacing, the expanded air will force the diaphragm, or a contact piece 19, against the screw tip. Thereupon a circuit will be completed and maintained until temperature falls, or circuit is broken, or the instrument is demolished.

While the diaphragm is herein shown and described as at the bottom of the expansion chamber of the device this is to be understood as merely relative and not a term of limitation, since diaphragm means may form seals at top, bottom, sides or ends of the sealed air space within device. The device may be placed in any desired position and the innumerable uses of the detector need hardly to be catalogued, but in Fig. 3

it is shown as installed between floor and ceiling space, where it will be effective to give an alarm when a predetermined temperature is reached.

5. What is claimed is:

An automatic fire alarm and detector comprising an imperforate head and a perforate manifold in spaced relation, a group of parallel thin metal tubes whose upper ends are seated air tight on the bottom face of the head and whose open lower ends lie in the apertures of the manifold, a thin diaphragm

lying close over the mouth of the tubes and below the manifold and forming a distensible circuit closer operative by slight expansion of air from any of the tubes, a clamp ring below the diaphragm, a set of clamp rods passing through the ring, the diaphragm and the manifold and engaging in the head, and contact bridge mounted on a pair of said rods and clamp nuts fastening the bridge, the ring, the diaphragm and manifold on said bolt rods.

HENRY PRADAS.
